CLAIM

The ornamental design for a coffee maker, substantially as shown and described.

DESCRIPTION

FIG. 1 is a perspective view of the coffee maker.

FIG. 2 is another perspective view of the coffee maker.

FIG. 3 is a further perspective view of the coffee maker.

FIG. 4 is a detailed view of a portion of the coffee maker.

FIG. 5 is a front view of the coffee maker.

FIG. 6 is a top view of the coffee maker.

FIG. 7 is a right side view of the coffee maker.

FIG. 8 is a left side view of the coffee maker.

FIG. 9 is a back view of the coffee maker.

FIG. 10 is a bottom perspective view of the coffee maker.

FIG. 11 is a perspective view of a carafe which is a part of the coffee maker, where the carafe is shown separately for ease of illustration of the claim.

FIG. 12 is a top perspective view of the carafe of FIG. 11.

FIG. 13 is a bottom perspective view of the carafe of FIG. 11.

FIG. 14 is a top view of the carafe of FIG. 11.

FIG. 15 is a front view of the carafe of FIG. 11; and,

FIG. 16 is a first side view of the carafe of FIG. 11, and an opposite side of the carafe is a mirror image of the first side illustrated in FIG. 16.

The drawings are lined for color, but only with respect to elements comprising an accent color. Other elements of the ornamental design are not limited to any particular color. The accent color is indicated with oblique lines, per MPEP

(Continued)

§ 608.02(IX), to indicate a brown color. The accent color may be any shade of brown, such as reddish brown, such as copper.
